J. HARASTA

CIGAR AND CIGARETTE LIGHTING DEVICE

Filed July 6, 1921

FIG-2-

Inventor

John Harasta

By *J. W. Bryant.*
Attorney

UNITED STATES PATENT OFFICE.

JOHN HARASTA, OF BINGHAMTON, NEW YORK.

CIGAR AND CIGARETTE LIGHTING DEVICE.

Application filed July 6, 1921. Serial No. 482,655.

To all whom it may concern:

Be it known that I, JOHN HARASTA, a citizen of Czechoslovakia, residing at Binghamton, in the county of Broome and State 5 of New York, have invented certain new and useful Improvements in Cigar and Cigarette Lighting Devices, of which the following is a specification.

This invention relates to certain new and 10 useful improvements in cigar and cigarette lighting devices and the invention relates particularly to a priming attachment for cigars or cigarettes to be sold with the cigarette or cigar in position to properly 15 light the same so as to avoid the necessity of using separate matches or the like.

The primary object of the invention is to generally simplify and improve devices 20 of the above kind.

Other objects will appear as the nature 25 of the invention is better understood, and the same consists of the novel form, combination and arrangements of parts hereinafter more fully described, shown in the accompanying drawing and claimed.

In the drawing, wherein like reference characters designate corresponding parts throughout the several views,

Figure 1 is a perspective view of a cigarette 30 having an igniting or priming attachment in accordance with the present invention,

Figure 2 is a view of the device shown in Fig. 1 partly in longitudinal section and 35 partly in side elevation, and

Figure 3 is a longitudinal sectional view 40 of the lighting attachment.

The present invention embodies a relatively small elongated body 5 formed of a compound which will readily ignite by friction 45 and having the middle portion 6 of a wire attaching device embedded therein, which attaching device also includes a pair of parallel spurs 7 extending in the same general direction as the longitudinal axis 50 of the body 5 and at each side of the latter as well as beyond one end of the same, the spurs 7 being arranged to be projected into one end of the cigarette 8 for attaching the igniting or lighting device to said cigarette 55 as shown in Figs. 1 and 2. The attaching device is preferably formed from a single piece of wire with its opposite ends forming spurs 7 and with the central portion 6

thereof twisted in the general form of the figure 8 so that said middle portion will be firmly embedded in the compound or body 5. The spurs 7 are somewhat similar in form to the hooked ends of fishing hooks so that the same may be readily inserted 60 into the end of the cigarette but will be prevented from ready detachment, and the compound or body 5 is made of such length as to partially enter the cigarette and to partially project beyond one end of the 65 latter.

In the use of the device, the lighting attachment is embedded in the cigarette as shown in Figs. 1 and 2 and when it is desired to light the cigarette, the body 5 is 70 rubbed upon a suitable surface so that it is ignited by friction and by then puffing the cigarette, the flame of the igniting device is imparted to the end of the cigarette.

It will be seen that the device is of such 75 simple and cheap construction and embodies such effective means for attachment to the cigarette, that the same will meet with all the requirements for a successful commercial use.

From the foregoing description it is believed that the construction and operation 80 as well as the advantages of the present invention will be readily understood and appreciated by those skilled in the art.

Minor changes may be made in the invention without departing from the spirit and scope of the invention as claimed.

What is claimed as new is:—

An igniting attachment for cigars and 90 cigarettes including an attaching member formed of a single piece of wire with a looped central portion and spur shaped parallel ends, a body of friction ignited material in which said central portion is embedded, said body being of elongated form, the central portion of the attaching device 95 simulating a figure 8 and the spur-shaped ends extending outwardly from the sides of the body and then rearwardly of the latter 100 in spaced relation, the said attaching member and igniting body being associated with said cigar or cigarette in such a manner that substantially one-half of the central part of said member and said body are embedded 105 in the end thereof.

In testimony whereof I affix my signature.
JOHN HARASTA.
